SPLITTER KNIFE

Edward M. Key, P.O. Box 292, McMinnville, Oreg.

Filed June 3, 1960, Ser. No. 60,836

Term of patent 14 years

(Cl. D22—3)

Fig. 2.

Fig. 1.

Fig. 3.

FIGURE 1 is a side view of the splitter knife, showing my new design, the opposite side being identical thereto; FIGURE 2 is an edge view as viewed from the left in FIGURE 1, the opposite edge view being identical thereto but inverted 180°; and

FIGURE 3 is a plan view as viewed from the top in FIGURE 1, the bottom plan view being identical but inverted 180°.

I claim:

The ornamental design for a splitter knife, as shown and described.
